UNITED STATES PATENT OFFICE.

ROBERT T. JOHNSTON, OF PLAINFIELD, NEW JERSEY, ASSIGNOR, BY MESNE ASSIGNMENTS, TO THE AUTOPLATE COMPANY OF AMERICA, OF JERSEY CITY, NEW JERSEY, A CORPORATION OF NEW JERSEY.

PRINTING-PRESS BED.

1,010,918.

Specification of Letters Patent.

Patented Dec. 5, 1911.

Application filed May 12, 1904. Serial No. 207,545.

To all whom it may concern:

Be it known that I, ROBERT T. JOHNSTON, a citizen of the United States, residing at Plainfield, in the county of Union and State 5 of New Jersey, have invented a new and useful Printing-Press Bed, of which the following is a specification.

The object of this invention is to provide an improved construction of a printing press 10 bed.

A printing press bed, as usually constructed, consists of a heavy form supporting part having side flanges and a ribbed lower surface; and extending from the supporting 15 part is a superstructure which carries or has formed with it an ink distributing table in the form of a large and heavy rectangular plate. As larger presses have been designed, so much difficulty has arisen from the ink 20 distributing tables getting out of shape that designers have been gradually increasing the weight of the superstructure and extending it out farther toward the end of the ink distributing table. Furthermore, so much 25 difficulty has been encountered in providing a rigid bed for supporting the forms that flanges have been put on the bottom of the ribs; or some builders have attempted to make that part of the bed which supports 30 the forms in the shape of a hollow casting. But this necessity of making the superstructure and the supporting part very solid to carry the ink distributing table accurately 35 and to resist the tremendous pressure from the impression cylinder during printing is opposed by the factor that the bed and the parts carried therewith should be made as light as possible so that the bed can be easily reciprocated and the press operated 40 at high speed without jar. In my application for patent filed May 3, 1904, Serial No. 206,127, I have shown, described and claimed an improved form of inking mechanism by 45 which the heavy ink distributing table has been omitted and whereby there is only a small rectangular ink plate or carrier carried by the bed at considerable distance 50 from the forms. In further carrying out said invention, I have found that I can materially lighten the bed and the parts which 55 move therewith by omitting said superstructure and by making the rectangular ink-plate an independent part provided with rollers running on the ways of the bed and by connecting said ink-plate to the bed by

bars or links so as to hold the ink-plate at the proper position relatively to the forms. These bars or links are arranged between the form-supporting part and the ink plate to allow a relative vertical movement between the parts so that the weight of the ink plate will not be carried by the form-supporting part. 60

In the attempts which have been previously made to lighten the bed proper by casting the same in the form of a hollow box, great complication has arisen in molding. To get the proper strength a large number of ribs are necessarily employed, while, on the other hand, to get the bed as 65 light as possible these ribs must be made as thin as it is possible for metal to run, hence, great difficulty has been encountered in properly supporting the cores during casting which makes this plan impractical. To 70 overcome this difficulty, I mold the bed in the upper and lower section and bolt them together. Each section is provided with transverse and longitudinal ribs which match 75 each other so that when the two sections are bolted or riveted together they form a light rigid cellular box-like structure without any opening on the sides or bottom. In this way the ribs of the bed can be made as light 80 as the casting can be poured. The top and bottom surfaces can be cast heavy and planed down to proper thickness. The planed surfaces of the top and bottom can be measured from the inside so that the same 85 can be finished of even thickness throughout, whereby it will be known precisely how the metal is distributed in the bed. The meeting faces of the ribs can be faced all over so that the two sections will properly 90 match. The parts, by being thus put together, are strengthened something like a shoe-box is strengthened when its cover is 95 put on. In this way, a much stronger and rigid structure is provided for the same 100 weight of metal as compared with the old devices. 105

Referring to the drawings and in detail, Figure 1 is a plan of a printing press bed constructed to embody my improvements. Fig. 2 is a side elevation thereof. Fig. 3 is a sectional view taken on the line 3—3 of Fig. 1. Fig. 4 is an enlarged sectional elevation taken on the line 4—4 of Fig. 1, and Figs. 5 and 6 show details hereinafter referred to. 110

In detail, A designates the bed-bottom which is provided with a series of longitudinal ribs a' and a series of transverse ribs a'' .

5 B designates the top part of the bed which is provided with longitudinal ribs b' and transverse ribs b'' to match the ribs a' and a'' . This part of the bed is provided with a solid surface so as to form an im-
10 perforate top or form-supporting surface.

The two parts of the bed are cast separately and are finished by planing. They then are laid face together and are secured to each other by patch bolts C driven into
15 reamed holes and by side screws D. The bottom of the bed A is provided with the usual ribs 10 in which are fitted steel shoes 11 which run on the usual rollers carried by the tracks of the frame, as shown in Fig. 3.

20 E designates the rectangular ink-carrier or plate. The same is provided with brackets 12 on its under side which carry rollers 13 which run on the second and fifth tracks, whereby the ink-plate is sup-
25 ported directly on these tracks and the usual superstructure extending out from the bed proper is not needed.

Ears 14 are cast on the lower section of the bed. Side bars or links 15 are piv-
30 oted thereto by a single bolt and the ends of said links are rigidly secured to the ink-plate E. Central ears 16 are also formed on the lower section of the bed and matching ears 17 on the ink-plate. Secured to
35 each of these sets of ears is a small piece 160 which has a central cylindrical portion 1600. A middle link 18 is fitted to these pieces 160. By this arrangement the side links 15—15 are pivoted to the bed and
40 rigidly secured to the ink-plate, while the middle link 18 is pivoted to both the bed bottom and ink-plate.

The usual registering racks 19 may be se-
45 cured to the sides of the bed, and exten-
sions 20 thereof which operate the dis-
tributing rollers of the form inking mech-
anism may be bolted to the side bars 15; the
50 joint between the racks 19 and 20 centering
on the bolt which pivots the links 15 to
the bed so as not to interfere with the
pivoted connection between the ink-plate
and the bed. 21 designates the rack hanger
55 which is secured to the bed to carry the
usual upper and lower racks for the main
driving mechanism and 22 designates a re-
versing rack which may be secured to the
bottom of the bed to make up the parts of a
60 bed-motion operating upon the principle of
that shown, described and claimed in my
application for patent filed January 27,
1904, Serial No. 190,812. These rack ar-
rangements form no part of the present im-
provement, which relates to the structure

of a printing press bed irrespective of the way the same is moved, and the aforesaid parts are indicated merely to show the points at which the same may be attached in practice.

By the before described arrangements, a printing press bed is provided which is very strong and rigid under impression and by which the usual superstructure extending from the bed is eliminated, and, at the same time, the parts are very light so that the bed can be reciprocated at high speed without jar.

The invention is particularly useful in large presses or those which are designed of considerable width to carry a large number of forms abreast.

The details, as herein shown and de-
scribed, may be greatly varied by a skilled
mechanic without departing from the scope
of my invention as expressed in the claims.

Having thus fully described my inven-
tion, what I claim and desire to secure by
Letters Patent is:—

1. A printing press bed made up of a form-supporting part, an ink plate having track-engaging means, and flexible con-
90 nections between the form-supporting part
and the ink plate.

2. In printing press construction, the combination of tracks, a printing press bed made up of a form-supporting part run-
95 ning on said tracks, an ink-plate independ-
ently fitted to run on said tracks, and flexi-
ble connections between the form-support-
ing part and ink-plate.

3. In printing press construction, the combination of the tracks, and a printing press bed comprising a form-supporting part running on said tracks, an ink-plate provided with rollers running on said tracks, and bars or links flexibly connecting 105 the ink-plate to the form supporting part.

4. In printing press construction, the combination of the tracks, and a printing press bed comprising the form supporting part, an independent ink-plate fitted to run 110 on said tracks, and hinged connections be-
tween the form supporting part and the
ink-plate.

5. A printing press bed made up of a form supporting part, an ink-plate, pivoted 115 connections between the ink-plate and form supporting part, racks secured to the sides of the bed, and extensions thereof secured to said connections.

In testimony whereof I have hereunto set 120 my hand, in the presence of two subscrib-
ing witnesses.

ROBERT T. JOHNSTON.
